SINKER HEAD FOR KNITTING MACHINES

Alvin L. Brumbach, Reading, Pa., assignor to Textile Machine Works, Wyomissing, Pa., a corporation of Pennsylvania

Application October 7, 1941, Serial No. 414,012

21 Claims.

(Cl. 66—110)

This invention relates to sinker-heads of full-fashioned and other flat knitting machines and this application is a continuation in part of my prior application for "Bearing construction for knitting machines," Serial No. 214,058, filed June 16, 1938, which has eventuated into Patent No. 2,271,852.

In the operation of certain types of knitting machines of which the full-fashioned machines are examples, the sinkers and dividers reciprocate on horizontal bearing portions of the sinker-heads. Said heads have ordinarily been made to include a lower cast metal bed or base and an upper cast metal top or cover. As the sinkers and dividers are commonly made of Swedish steel and are very thin, they have a marked grooving action on their bearings or supports. Also, the sinkers and dividers themselves wear somewhat at the same time. The sum of the wear on the supporting areas and on the lower edges of the sinkers and dividers affects the position of the thread catching notches of the sinkers and dividers to lower them, but somewhat irregularly, thereby lowering the grade of the hosiery produced. In attempting to recondition worn sinker-heads, difficulty has been encountered for several reasons, one being because it has been the custom to machine the sinker-head bases and covers to provide guide grooves for the sinkers and dividers and, when once the original grooves have worn beyond a certain degree, it is almost impossible to recondition a head so that it gives perfect results again for a commercially significant period merely by further machining of the original slots and correspondingly elevating the head, because the slots wear wider as well as deeper.

It is accordingly an object of my invention to provide a sinker-head structure adapted for full-fashioned and other knitting machines having a readily removable insert portion and which can be restored to its original condition at an advantageous cost after its bearing surfaces have been changed by use to a degree causing an undesirable effect on the quality of the product.

Another object is to provide a sinker-head having a readily removable slotted insert for supporting the entire number of sinkers and dividers and which can be replaced, after the slots have been worn, at a cost less than that of a new sinker-head.

Another object is to provide a novel sinker-head which can be made economically and which can be economically restored to its original condition.

Still another object is to provide a novel sinker-head arrangement in which the bottom edges of the sinkers and dividers shall rest and reciprocate on a plane surface instead of in grooves.

A still further object is to provide a form of sinker-head insert unit adapted for a full-

fashioned knitting machine which will require less expense than the present form of sinker-head to machine to final dimensions.

A still further object is to provide an insert in a sinker-head to accomplish the various advantages, apparent from the following description.

With these and other objects in view, which will become apparent from the following detailed description of the illustrative embodiments of the invention shown in the accompanying drawings, my invention resides in the novel structures including the new elements, features of construction and arrangement of parts in cooperative relationship as hereinafter more particularly pointed out in the claims.

In the drawings:

Fig. 1 is a top plan view of a sinker-head structure, embodying the invention, having distance breaks indicating a contraction of the length thereof to simplify illustration; the structure forming part of a well known multi-section full-fashioned knitting machine;

Fig. 2 is a sectional view having a portion taken substantially along the line 2—2 of Fig. 1, and a portion of a needle bed structure not shown in that figure;

Fig. 3 is a detail fragmentary sectional view taken substantially along the line 3—3 of Fig. 1 and enlarged relative thereto, the sinkers and dividers being omitted;

Fig. 4 is a perspective view, having an intermediate break, of a sinker bed cover insert of the invention;

Fig. 5 is a view similar to Fig. 4 of a sinker bed insert, also of the invention;

Fig. 6 is a perspective view of a modified form of the invention, showing a sinker bed cover insert-receiving element in dot-and-dash lines, and an insert molded thereto;

Fig. 7 is a perspective view of a sinker bed unit according to the form of the invention of Fig. 6, showing a non-metallic sinker guide insert molded to a metal receiving element therefor;

Fig. 8 is a view of the structure of, and as viewed in, Fig. 7 taken in section along the line 8—8;

Fig. 9 is a view similar to Fig. 2 of another form of the invention;

Fig. 10 is a view similar to Fig. 9, of a further form of the invention;

Fig. 11 is a view similar to a portion of Figs. 9 and 10, of a still further form of the invention;

Fig. 12 is a top plan view similar to Fig. 1, of another form of the invention, showing a sinker-head having spacer elements for the sinkers and dividers;

Fig. 13 is a sectional view similar to Fig. 2, taken, substantially along the line 13—13 of Fig. 12;

Fig. 14 is a sectional view similar to Fig. 3.

taken substantially along the lines 14—14 of Fig. 12;

Fig. 15 is a fragmentary detail sectional view similar to a portion of Fig. 13, but taken on a different section line and enlarged relative thereto, with the parts in different relative positions and certain of the parts broken away;

Fig. 16 is a detail view of one of the spacer elements shown in Figs. 12 to 15;

Fig. 17 is an end view of a spacer element as viewed from the right of Fig. 16;

Fig. 18 is a cross-sectional view similar to a portion of Fig. 14 and enlarged relative thereto;

Fig. 19 is a fragmentary detail view in elevation of a combined spacer and tie bolt shown in Fig. 15;

Fig. 20 is a perspective view of a sinker bed cover according to the form of invention of Figs. 12 to 15, part being in vertical section and part in transverse section;

Fig. 21 is a perspective view of a sinker bed unit according to the form of invention of Figs. 12 to 15;

Fig. 22 is a perspective view of an insert member shown in Fig. 20;

Fig. 23 is a sectional view taken along the line 23—23 of Fig. 22 indicating by cross-hatching one material from which the insert member is constructed; and

Figs. 24 and 25 are sectional views similar to Fig. 23 indicating by different cross-hatching different materials from which the insert member of Fig. 22 may be constructed.

In the drawings and description, only the means necessary to a complete understanding of the invention have been specifically set forth; further information as to the construction and operation of other related, usual and well known knitting machine elements, mechanisms, etc., may be found in one or more of the following publications:

1. Pamphlet entitled—Full-Fashioned Knitting Machines—published and copyrighted by the Textile Machine Works, Reading, Pennsylvania, in 1920.

2. Three catalogs entitled—The “Reading” Full-Fashioned Knitting Machine Parts Catalog—published and copyrighted by the Textile Machine Works, in 1929, 1935 and 1940, respectively.

3. Booklet entitled—The “Reading” High-Production Full-Fashioned Knitting Machine—which forms a supplement to the above noted 1940 parts catalog of the Textile Machine Works, and which booklet is a publication of the Textile Machine Works, and was copyrighted by the latter in 1940.

4. Pamphlet—Knitting Machine Lectures—published by the Wyomissing Polytechnic Institute, Wyomissing, Pennsylvania, in 1935.

Referring to the drawings, I have shown there in several sinker-heads according to my invention, said heads being of different forms but all adapted for use in a full-fashioned knitting machine and providing a horizontal supporting means for the lower edges of the horizontally reciprocating sinkers and dividers as well as guiding means for the lateral edges and/or sides of the sinkers and dividers.

Figs. 1, 2 and 3 of the drawings illustrate a sinker-head assembly S embodying the invention; Fig. 2 showing this structure in cooperative relation to a needle bar assembly N, and a knockover bit assembly K, each constituting a

part of a multi-section full-fashioned knitting machine, as set forth in the above-mentioned catalogues, except for the improvements in the sinker-head herein set forth.

The needle bar assembly N comprises a needle bar 7, a needle bed 8, needles 9, a yieldable needle clamping strip 12, as of paper, and clamps 14 held to the bar 7, as by screws 15.

The knockover bit assembly K comprises a knockover bit bed 17, knockover bits 18, and a knockover bit clamp 19.

The sinker-head assembly S, which is mounted on a center bed 22 of the machine, comprises, in the structure illustrated, a sinker bed backing member or base 23 for a sinker bed insert 24, sinkers 27, dividers 28, a sinker-bed cover backing member 29, sinker-bed cover insert 32, and a verge plate 33. It will be noted that the backing member 23 and insert 24 comprise the bed or base B of the assembly S, portion B ordinarily being made in one piece.

The sinker bed backing member 23 has apertured lugs 37 through which screws (not shown) extend to secure the member 23 to the center bed 22.

The sinker bed cover backing member 29 is mounted in superposed spaced relation to the member 23 by spacers 38 (Fig. 3), screws 39, and spacer bolts 40.

The sinker bed backing member 23 is, in the present instance, composed of metal having a hollowed out top portion or face for the reception of the insert 24, which is of accurately-machinable or formable non-metallic material, such as, phenolic condensation products of the type generally recognized in the trade under the trade-names of “bakeelite,” “textolite” and the like, Celluloid, composition, or other accurately-machinable substance of wear resistant, and hard, or distortion opposing, characteristics. Depending portions 42 and 43 (Figs. 2 and 5), of the insert 24, hold or lock the insert against displacement, relative to the backing member 23, in the direction of the forward and backward movement of the sinkers 27 and the dividers 28.

Also, at the front end of the insert 24, the latter is extended forwardly and upwardly to form a presser edge 44 the function of which is, as is well known, to engage the beards of the needles on the down stroke of the needles to close the beards by pressing their ends into the grooves in the upper portions of the needle bodies.

After the underside surfaces of the insert 24 have been accurately machined, for close precision fit to the cooperating similarly machined surfaces of the backing member 23, the members 23 and 24 are secured to each other, as by screws 47 that are disposed partially in apertures 48 in the member 23, and partially in countersunk openings 49 in the insert 24.

With the backing member 23 and the insert 24 thus assembled, they are then machined and finished, the same as though they were of one integral metal piece, to form sinker and divider grooves 52, and to have them of proper shape and dimension in every other particular. The cover backing member 29, and the cover insert 32, are made, fitted, assembled and finished similarly to the members 23 and 24, to form a cover C having sinker and divider grooves 58 in the insert 32.

The sinker-heads of full-fashioned knitting machines, as is well known, have a sinker or divider mounted in alignment with the gap be-

tween each pair of needles. Also, the number of the gauge of a full-fashioned knitting machine is equal to the number of needles in one and a half inches. Assuming therefore that a sinker-head assembly 8 for a 38 gauge machine is shown in the drawings, the grooves 52 and 58 in the inserts 24 and 32 respectively are machined twenty-six per inch. For the now more popular higher gauge machines, the grooves are set even closer.

The bolts 48, since they extend through the member 28, the inserts 32 and 24, and the member 23, in the working zones of the sinkers and dividers, are each therefore provided with a thin plate-like intermediate section 66 to fit between a sinker and a divider. Also, since in this position, they must not turn, the bolts 48 are each provided with square-section portions 68 fitting square openings 63 and 64 in the inserts 24 and 32, and the backing members 23 and 28, respectively. Disk like heads 65 of the bolts 48 are held against the member 23 by nuts 66.

At its rear edge, the insert element 32 has an inclined bearing surface portion 53 for an impact reducing portion 54 of the verge plate 33 having an impact insert 57 which may also be constructed of material similar to the material of the inserts 24 and 32. The major portion of the verge plate 33 is in rigid stationary position on the backing member 23, but the portion 54, having some impact movement when engaged by the sinkers and dividers, is mounted for such movement on the bearing portion 53 of the insert 32. The backing member 23 and the insert 32, which guide the sinkers and dividers, are secured to each other by screws 58, in openings 59 of the insert with a ledge 62 on the insert (Figs. 2 and 4) engaging an edge 63 of the backing member.

In the form of the invention illustrated in Fig. 6, an insert element 67 for the cover, shown in full lines and constructed of the non-metallic material above set forth, is molded to a metal insert-receiving backing member 68, shown in dot-and-dash lines. The latter is provided with dove-tail grooves on its surface next to the insert element 67, such that when the latter is molded in position, ridges 69 are formed in, and coact with, the grooves in the element 68 as anchorage means for holding the elements 67 and 68 together.

The sinker bed cover assembly of Fig. 6, composed of element 67 and member 68, is first formed to its general shape, and subsequently accurately machine finished as one piece and provided with sinker and divider grooves 12.

As shown in Figs. 7 and 8, a sinker bed unit is formed similarly to the sinker bed cover unit of Fig. 6, by an insert-receiving backing member 73 of metal, and an insert member 74 of non-metallic material, as set forth; the insert, in this instance also, having ridges 77 dove-tailed into grooves in the receiving member to hold the members together. Depending integral bearing portions 78 and separate cooperating bearing elements 79, of non-metallic or metallic material, secured to the portions 78 by screws 82 adapt the assembly as a mounting for the customary knock-over bit trunnions (not shown) of the machine. The sinker bed unit of Figs. 7 and 8 is formed to its general shape, and subsequently accurately machine finished and provided with a presser edge 75 and sinker and divider grooves 12.

In Fig. 11, I have shown a sinker-head 8A within the invention, differing from that shown in Figs. 1, 2 and 3 primarily in the proportions

of the parts, the knockover bit bed and needle bar being, however, omitted from this figure. In the arrangement shown in Fig. 11, the backing member 23A extends farther forward and rearward beneath the insert 24A than does member 23 beneath member 24, thereby rendering greater support to the insert member, the insert member having a straight plane bottom to permit of the stated arrangement of the backing member, and both the backing member and insert of Fig. 11 are arranged for only one row of holding screws 47A instead of two. The cover backing member 29A and the cover insert 32A of Fig. 11 are substantially like those of Figs. 1, 2 and 3, except that they also have one row of screws 58A instead of two. The verge plate arrangement shown in Fig. 11 is somewhat different from that shown in Figs. 1, 2 and 3. This, however, forms no part of the present invention and is not described or claimed herein.

In Fig. 9, I have shown a form of sinker-head SB within the invention identical with that in Figs. 1, 2 and 3 except that the insert parts 24B and 32B are made of metal.

In Fig. 10, I have shown a form of sinker-head SC quite like those shown in Figs. 2 and 9, but in which the metal insert members 24C and 32C are held in place by sweated or soldered joints 85 and 86, respectively. When it is desired to separate inserts 24C and 32C from their backing members, it is necessary only to bring their temperature up to the point at which the solder in joints 85 and 86 becomes molten and to insert a sharp pry between the inserts and the backing members.

In all the forms shown in Figs. 1 to 11 inclusive, the insert members, whether of Bakelite or metal, are formed with slots for receiving the edges of the sinkers and dividers and for guiding and supporting them during their reciprocation.

In Figs. 12 to 25 inclusive, I have shown a form of sinker-head SD within the invention comprising a metal base member 90 having a plane horizontal upper surface 91 interrupted by one or more longitudinal grooves 92 of which two are shown. The cover or cap member 93 is arranged or formed similarly to the base member 90, the bottom of the cover 93 being a plane horizontal surface 94 but interrupted by only a single longitudinal groove 95, spacer blocks 106 and screws or bolts 107 near the ends of parts 90 and 93 holding them in proper spaced relation similarly to spacers 38 in Fig. 3. Top surface 91 of the base is evidently well adapted to support the lower edges of the sinkers 27 and dividers 28 for horizontal reciprocation, but can have no effect in maintaining the desired spacing between them or in maintaining them in vertical planes transverse to base 90, as is necessary. For these purposes, I have shown spacer members 96 which extend at points of maximum width continuously from surface 91 to surface 94 in the vertical direction and extend at full width in the direction transverse to the sinker-head and parallel to the sinkers for a considerable portion of the width of member 93, for over half of such width in the arrangement shown. The thickness of members 96 is approximately that of the ribs between slots 52 and 58 (Fig. 3) for the same gauge machine. The clearances between the spacers 96 and the sinkers 27 and dividers 28 being therefore quite small as shown and such clearances being covered at top and bottom, they become completely filled in use with lubricant films so that the sinkers and dividers run in contact with lubricant films

throughout their entire widths for material portions of their lengths and are thereby protected by the lubricant from shocks and wear to a surprising extent. Such films being, of course, very thin no attempt has been made to show them. As perhaps is best shown in Figs. 14 and 18, spacers 86 are arranged in vertical planes one on each side of each sinker 27 and divider 28. Spacers 86 in turn are held in their proper spacing and in vertical planes by means associated with said grooves 92 and 95 and comprising insert strips 97 and 102 in grooves 92 and 95 respectively which make only a moderately close fit with the walls of said grooves so that they can be readily inserted therein and removed therefrom. While the forward insert member 97 is functionally identical with the rear insert member 102, said rear insert member is shown shortened and bevelled at its ends at points 115 so as not to interfere with the means ordinarily employed for securing the sinker-heads to the center bed 22. Said inserts 97 and 102 have transverse slots 98 therein separated by thin ribs 99, of about the thickness of the sinkers and dividers. When inserts or strips 97 and 102 are in place in grooves 92 and 95, slots 98 and ribs 99 extend transversely of both said inserts and the members 90 and 93 as well as parallel to the line of movement of the sinkers and dividers, the sinkers 27 and dividers 28 lying in the same vertical planes as the ribs 99. However, as is perhaps best shown in Figs. 15 and 18, the sinkers and dividers do not contact the edges of ribs 99, being supported entirely by the base 90 and sliding back and forth on its said upper surface 91 when in operation. The upper edges of sinkers 27 and dividers 28 do not quite contact with the bottom surface 94 of cover member 93 but there is not clearance enough to be shown conveniently in the drawings. Ribs 99, however, are preferably not cut down or back relatively to the remainder of inserts 97 and 102, the inserts being shown of the same thickness in the intermediate portions containing slots 98 as in their end portions 101. Further, as is clear from Figs. 13, 14, 15 and 18, insert 102 in groove 95 in cover member 93 is identical with one of inserts 97 except that insert 102 is, of course, inverted compared to inserts 97 so that the slots 98 in insert 102 open downward instead of upward.

In order to promote the ready assembly of spacers 86 in the desired positions as shown as well as to hold the spacers and the inserts 97 and 102 against movement in the members 90 and 93, spacers 86 each have lower projections 103 and an upper projection 104, said projections extending into slots 98. Projections 103 and 104 fit into said slots 98 somewhat loosely, so that the parts can be readily assembled, but closely enough so that spacers 86 and the sinkers 27 and dividers 28 are held in substantially vertical planes. Movement of the assembled inserts 97 and 102 with the spacers 86, the sinkers 27 and dividers 28 lengthwise of members 90 and 93 is prevented by those of spacers 86, designated 96A, which lie in the end slots 98 and engage with their outer vertical sides the inner sides of spacer blocks 106, Fig. 14. Also while spacers 86 rest on surface 91, inserts 97 rest on the bottoms of grooves 92, and insert 102 is supported by projections 104 of spacers 86, the lower edges of projections 103 not generally contacting the bottoms of grooves 98 in inserts 97.

As is well known, the sinkers 27 are reinforced at their rear ends by angular plates 116, often called "sinker backs." In order that spacers 86

may extend to the rear as far as possible, they are cut out at their rear ends to provide recesses 111 in which plates 116 may reciprocate without mechanical interference.

While spacer bolts are not considered as important in the sinker-head arrangement SD shown in Figs. 12 to 25 inclusive, as in the arrangement shown in Figs. 1, 2 and 3, I have shown a spacer bolt in Figs. 12, 15 and 19. Owing to the use of plate type spacers in the arrangement shown in Figs. 12 to 25 inclusive, it is necessary that the bolting means be combined with one or more spacers. As shown, a spacer 96B has small integral extensions 116 and 117 on its lower and upper edges, respectively, to which are attached, as by welding or brazing, square bolt sections 118 adapted to occupy square holes 121 and 122 in members 90 and 93, respectively. Round threaded extensions 119 integral with square sections 118 run through members 90 and 93 into recesses countersunk therein and receive nuts 123 and 124, respectively, thereon for preventing cap portion 93 from springing out of parallel with portion 90.

The inserts 97 and 102 may be made of any convenient material. In Figs. 23, 24 and 25, I have shown in section several insert members 97 and 102 which are identical except for the materials of which they are made, Fig. 23 being cross-hatched to indicate that the insert shown therein is made of brass, Fig. 24 being cross-hatched to indicate that the insert shown therein is made of steel, and Fig. 25 being cross-hatched to indicate that the insert shown therein is made of Bakelite. Moreover, if desired, inserts 97 and 102 may be die-cast or made by compressing powdered metal. The spacers 86 may be conveniently stamped or cut from thin sheet material by a die. Also, spacers 86 may be made of metal or Bakelite as desired, those shown being of metal. Further, spacers 86 may be made by die-casting if desired. Similarly, although the base 90 is assumed to be of a bearing metal such as hard brass or bronze, this member may be made thinner in the vertical direction than shown, if desired, and the difference in its vertical dimension compared to that shown made up in Bakelite placed along its upper surface 91, the surface presented to the edges of sinkers 27, dividers 28 and spacers 86, so that the bearing surface for the sinkers and dividers will be Bakelite, as is the case in the sinker-heads shown in Figs. 1, 2, 3 and 11. Also, if desired, cover 93 may be made thinner than shown and have a sheet of Bakelite along its bottom surface. Whenever Bakelite is used as a bearing for the lower edges of the sinkers and dividers, the coefficient of friction of the metal of which the major portion of the sinker-head base and cover are made is immaterial and it can be of cast iron or can be of metal suitable for die-casting if desired. Further, the forward ends of spacers 86 can be made of Bakelite even if the spacers are mostly of metal. In this way, the presser surfaces for the needle beards may be made of Bakelite in the sinker-head SD shown in Figs. 12, 13 and 15 as well as in the forms shown in Figs. 1, 2, 3 and 11.

It will be seen that the arrangement of Figs. 12 to 25 inclusive is well adapted to rehabilitation in more than one way. After surface 91 has become so worn that the fabric produced is not of as high quality as desired, assuming surface 91 to be of metal, the original surface can be restored readily because the major part of it is protected from wear and the grooves which have been worn in it can be removed by merely ma-

ching the top of base 90 down to a smooth surface and raising the level of the sinker-head to correspond to the amount taken off. The inserts 97 are enough thinner than the depth of grooves 92 to permit truing up surface 91 at least once without requiring any change in strips or inserts 97. However, when necessary strips 97 can be made thinner, preferably by taking material off their bottoms.

If surface 91 is originally supplied by a sheet 10 of Bakelite, evidently, it can be restored by merely substituting a new sheet for the original one.

In case spacers 98 become worn, they can be readily replaced.

In the case of any of the forms shown, new 15 sinkers and dividers will, in general, be supplied at the time the supporting member is restored.

Further, it will be clear as to the form of the invention shown in Figs. 12 to 25 inclusive that the spacers 96, while considerable in number, are all identical. Also, the insert members 97 and 102 have identical machine work except for the minor operation of making the bevels 115. Further, surfaces 91 and 94, being plane ones, can be formed by grinding on a machine, by milling or equivalent method. Also, the grooves 92 and 95 can be cast in members 90 and 93 and finished by grinding, while the inserts 97 and 102 can be of ordinary brass drawn to size and requiring no machining except for making slots 98. Therefore, all points being considered the cost of a new sinker-head SD is less in quantity than the ordinary form because making the spacers 96 involves, after a proper die has been made, only a stamping operation, and the inserts 97 and 102 for the base and cover of a given head can be machined simultaneously in one operation.

It will be noted that all forms of sinker-head disclosed herein include inserts which are readily put on and removed from the base or cover backing members. This is true even of the inserts of Bakelite molded in place on the backing members, because such inserts can be readily chipped off when it is desired to replace them on account of their having become worn beyond commercial limits. It will be noted further that the slotted inserts 97 and 102 shown in Figs. 13, 14, 15 and 18 to 25 inclusive, while not in contact with the sinkers and dividers are nevertheless a part of the guiding means therefor in that said inserts hold the guiding spacers 98 in correct position by means of slots 98 and ribs 99.

The base member 90, as best shown in Fig. 21, has a pair of depending lugs 78 integral therewith, lugs 78 having cap pieces 79 fixed thereto by screws 82 serving to provide the journal bearing for the knockover bit bed (not shown) associated with the sinker-head SD, this being the ordinary arrangement as shown also in Figs. 7 and 8.

Of course, the improvements specifically shown and described by which I obtain the above results, can be changed and modified in various ways without departing from the invention herein disclosed and hereinafter claimed.

I claim as my invention:

1. A sinker-head adapted to support the sinkers and dividers of a full-fashioned knitting machine comprising a backing member and an insert firmly secured thereto but readily removable therefrom which has slots therein extending transversely of the head, said insert secured to said backing member by a soldered joint, and means for guiding said sinkers and dividers including said slots.

5 2. A sinker-head adapted to support and guide the sinkers and dividers of a full-fashioned knitting machine comprising upper and lower backing members, inserts firmly secured thereto and readily removable therefrom which have slots therein, extending transversely of the head, and spacer members lying between the positions of the sinkers and dividers and having projections extending into said slots.

3. A sinker-head adapted to support the sinkers and dividers of a full-fashioned knitting machine comprising upper and lower backing members, inserts firmly secured thereto but readily removable therefrom which have slots therein extending transversely of the head, and spacer members lying between the positions of the sinkers and dividers and having projections extending into said slots, said spacer members having recesses extending forwardly from their rear ends to receive the reinforcing members at the rear ends of the sinkers.

20 4. A sinker-head adapted to support and guide the sinkers and dividers of a full-fashioned knitting machine comprising a backing member having a substantially plane surface for supporting the sinkers and dividers and having parallel grooves therein sunk below the level of said surface and extending longitudinally of the head, transversely slotted strips in said grooves, and spacer members resting on said surface for separating the sinkers and dividers and having projections extending into the slots in said strips.

25 5. A sinker-head structure adapted to support and guide the sinkers and dividers of a full-fashioned knitting machine comprising a backing member acting as a base for the sinker-head and having a substantially plane surface for supporting the sinkers and dividers, and having parallel grooves therein sunk below the level of said surface and extending longitudinally of the head, a second backing member above said first backing member and acting as a cover for the sinker-head structure and having a groove set into its bottom surface parallel to said grooves, a transversely slotted strip in each of said grooves, means for holding said backing members in spaced relation, and spacer members resting on said surface for supporting the sinkers and having projections extending into the slots in said strips.

30 6. A sinker-head structure comprising spaced parallel elongated members arranged so that one member guides one edge and the other member the other edge of each of the sinkers, and parallel spacers intermediate said members having guiding and supporting contact with said sinkers over the entire widths of the sinkers for portions of the lengths of the spacers beginning adjacent the forward edges of said members.

35 60 7. In a flat knitting machine, the combination of a sinker-head having spaced elongated parallel cap and base members, a plurality of sinkers mounted to reciprocate in planes transverse to said members and having notched ends for engaging yarn, and thin parallel spacers held firmly between said members having guiding and supporting contact with said sinkers over the entire widths of the sinkers for portions of the lengths of the spacers beginning adjacent the forward edges of said cap and base members.

40 8. In a flat knitting machine, the combination with sinkers of a sinker-head structure therefor comprising spaced parallel elongated members arranged so that one member guides one edge and 45 the other member the other edge of the sinkers,

and parallel spacers intermediate said members in planes substantially perpendicular thereto and having guiding and supporting contact with said sinkers over the entire widths of the sinkers for at least portions of the lengths of the spacers, said sinkers mounted to reciprocate between said spacers and terminating substantially at the rear ends of their backs.

9. A sinker-head structure comprising spaced base and cover members having parallel plane surfaces, a series of spacer members held between said members in spaced parallel relation, and a series of sinkers arranged to reciprocate between said spacers, said spacers being cut out at their rear ends to avoid interference with reinforcing plates on the sinkers.

10. A sinker-head structure comprising spaced parallel elongated members arranged so that one member guides one edge and the other member the other edge of each of the sinkers, and spacer means extending intermediate said members and having guiding and supporting contact with said sinkers over the entire widths of the sinkers for a material portion of the length of the spacer means beginning adjacent the forward edges of said members.

11. A relatively thin elongated spacer member adapted for use in a sinker-head of a full-fashioned knitting machine for separating sinkers and dividers and having projections on its opposite relatively long edges adapted to engage members above and below the spacer.

12. In a full-fashioned knitting machine, the combination with a sinker-head having spaced base and cover members, parallel sinkers mounted to reciprocate between said members and guided thereby, and means for clamping said members together of a series of separable spacers arranged intermediate said sinkers, said spacers having upper and lower surfaces respectively in juxtaposition with the inner surfaces of said base and cap members in use and held in desired position transversely of said members in use by means recessed in one of said members.

13. In a full-fashioned knitting machine, the combination with a sinker-head having base and cover members, parallel sinkers mounted to reciprocate between said members and guided thereby and means for clamping said members together of a series of separable spacers arranged intermediate said sinkers, said spacers having upper and lower edge surfaces closely adjacent the inner faces of said cover and base members respectively and having projections extending beyond said upper and lower surfaces and into recesses in said base and cover members in use.

14. In a knitting machine, the combination of a sinker-head structure comprising spaced base and cover members having parallel inner guide surfaces, sinkers and dividers adapted to reciprocate in contact with said surfaces, and a series of spacer members separate from but held between said members in spaced parallel relation, said spacer members having vertical side surfaces for guiding said sinkers and dividers extending uninterruptedly substantially the entire distance between said base and cover members for at least half the width of said cover member and having projections extending beyond the guide surfaces of said base and cover members.

15. In a sinker-head structure for a knitting

machine, a backing member having a longitudinal recess therein, a transversely slotted insert in said recess, and spacer members having edge surfaces in juxtaposition with the inner surface of said backing member, said spacer members interengaged with said insert.

16. A sinker-head structure comprising spaced base and cover members having parallel plane surfaces, a series of spacer members separate from but held between said members in spaced parallel relation and extending at right angles to said surfaces and adapted to contact the sinkers and dividers substantially uninterruptedly for their entire dimension in the direction at right angles to said surfaces for a substantial longitudinal portion of the spacer members.

17. A relatively thin elongated spacer member adapted for use in a sinker-head of a full-fashioned knitting machine for separating and guiding sinker and divider members and having a cut-out at its rear end to avoid interference with reinforcing plates on the sinkers.

18. A sinker-head structure comprising spaced parallel elongated members arranged so that one member guides one edge and the other member the other edge of each of the sinkers, spacer members extending intermediate said members and having guiding and supporting contact with said sinkers over substantial portions of the widths of the sinkers for material portions of the length of the said spacer members and means for maintaining said spacer members in desired position relative to each other in use including projections extending from the spacer members beyond the facing portions of said elongated guide members.

19. A sinker-head structure comprising spaced parallel elongated members arranged so that one member guides one edge and the other member the other edge of each of the sinkers, spacers extending intermediate said members and having guiding and supporting contact with said sinkers over material portions of the widths of the sinkers for material portions of the length of the spacers, and anchorage means fixing said spacers to said members in use.

20. A relatively thin elongated spacer member adapted for use in a sinker-head structure and having a portion of a thickness suitable for separating reciprocating sinker and divider members in use and a width suitable for providing guiding and supporting contact with such members over substantially the entire widths of the sinker and divider members for a material portion of the length of the spacer member and having a cut-out at its rear end to avoid interference with a reinforcing plate on one of said reciprocating members.

21. A sinker-head structure for flat knitting machines comprising first portions guiding each one edge of a sinker or divider member, second portions guiding each the other edge of the sinker or divider member, and third portions extending intermediate said first and second portions and maintained at fixed distances apart in use for spacing each of the sinker and divider members one from the other and having guiding and supporting contact with both sides of each of the sinker and divider members over substantially the entire widths thereof for material fractions of the length of the spacer portions.
